(57) **CLAIM**

The ornamental design for a tent, as shown and described.

DESCRIPTION

FIG. 1 is a front elevational view of a tent of the present invention including a fly;

FIG. 2 is a right side elevational view of the tent of FIG. 1, the left side elevational view being a mirror image thereof;

FIG. 3 is a rear elevational view thereof;

FIG. 4 is a top plan view thereof;

FIG. 5 is a bottom plan view thereof;

FIG. 6 is a front elevational view with a portion of the fly cut away to show one of three curved poles which support the fly;

FIG. 7 is a front elevational view with the fly and curved poles removed;

FIG. 8 is a right side elevational view of the tent of FIG. 7, the left side elevational view being a mirror image thereof;

FIG. 9 is a rear elevational view thereof; and,

FIG. 10 is a top plan view thereof.
